CEMETERY TENT
Filed July 31, 1926

UNITED STATES PATENT OFFICE.

JAMES M. DODDRIDGE, OF MILTON, INDIANA.

CEMETERY TENT.

Application filed July 31, 1926. Serial No. 126,147.

The object of my present invention, broadly speaking, is the provision of a tent enclosure, for use in connection with interments in cemeteries, whereby the friends viewing the interment will be protected from unfavorable climatic conditions, and at the same time providing means whereby the earth which is removed to form the grave will be entirely hidden during the interment; also that the removed earth will be prevented from damaging the grass where it is placed, that is preventing the dirt from coming into contact with the grass around or near the grave; and to prevent the removed earth from becoming wet from rain or snow before it is returned to the grave, that is during the time it is removed.

Other objects and particular advantages of the invention will be suggested in the course of the following description.

One manner of carrying out the principles and objects of my invention in a practical way is shown in the accompanying drawings, in which—

Figure 1 is a plan view showing my tent with the top or cover removed, and showing the interior arrangement thereof, also showing an open grave, with the usual frame or run-boards therearound, and showing the location of the earth removed from the grave opening.

Figure 2 is a cross section of the same, the same being taken through the grave and the earth which has been removed.

Figure 3 is a perspective detail showing the manner of hanging the curtains or side walls and other parts. Figure 4 is a perspective view of the upper portion of one of the supporting posts, showing the manner of detachably connecting the curtain supporting means.

Figure 5 shows one edge portion of certain of the curtains which are provided with revolvable heads for securing certain parts together. Figure 6 shows a curtain edge which is opposite to that shown in Fig. 5, which latter is provided with slotted eyes to receive said heads. Figure 7 is a side elevation of one of said revolvable heads in elevation. And Fig. 8 is a perspective view

of portions of a side curtain and the top of the extension.

Similar indices denote like parts throughout the several views.

In order that the construction, the operation, and the several advantages of my invention may be more fully understood and appreciated, I will now take up a detailed description thereof, in which I will set forth the same as comprehensively as I may.

In the drawings letter A denotes the ground line or surface, which is usually covered with natural grass. Letter B denotes a grave, which has been excavated to the proper depth, and it is of the usual dimensions. Letters C, D, E and F denote the four run-boards, which surround the grave and rest on the surface A, in the usual manner. And H denotes the soil which has been removed. The main portion of my tent includes the corner posts 1, 2, 3 and 4, and the intermediate posts 5 and 6, all of which are identical with each other. Each of said posts has a pintle 7 extending upward from the center of the upper end thereof.

Connecting each two of said posts is a rope or cable. The rope 8 connecting the posts 1 and 2; the rope 9 connecting the posts 2 and 6; the rope 10, connecting the posts 6 and 3; the rope 11, connecting the posts 3 and 4; the rope 12, connecting the posts 4 and 5; and the rope 13, connecting the posts 5 and 1.

A ring 14 is secured on each end of each of said ropes, which rings are adapted to surround the respective pintles 7 and rest on the ends of the respective posts, as shown in Fig. 4.

Each of the posts 1, 2, 6, 3, and 4 is provided with a guy-rope 15, which extend downward at an angle to the ground, where they are secured to their respective stakes 16, as indicated.

Extending between the posts 1 and 2 is an end curtain 17; extending between the posts 2 and 6 is a side curtain 18; extending between the posts 6 and 3 is a side curtain 19; extending between the posts 3 and 4 is an end curtain 20; and extending be-

tween the posts 4 and 5 is a side curtain 21. Also a side curtain 25 extends between the posts 1 and 5. Each of said curtains is provided on its upper edge with a plurality of hooks 22, which are adapted to engage over the respective ropes 8, 9, 10, 11, 12 and 13, whereby said curtains are suspended, extending to the ground A.

The adjoining edges of each two of said curtains are adapted to be connected by snaps or a head and eye, shown in Figs. 5, 6 and 7.

Numerals 23 denotes the roof, whose lower edges extend over the upper edges of the respective curtains, where they are detachably secured in any well known manner, as by said heads and eyes. The roof is supported by the center pole 24, from which it slopes downward in each direction.

All of said parts may be constructed and arranged as desired, as I make no claim thereto, and am not to be limited thereby.

The invention proper resides in that which I will now describe, and comprises the following: Numeral 26 denotes an angularly disposed curtain or cover, the same having a plurality of hooks 27, identical with the hooks 22, secured to its upper inner edge and adapted to be engaged over the rope 13, with the member 26 extending between the posts 1 and 5, with its edges adapted to be detachably connected with the edges of the curtains 17 and 21. Said curtain and cover is identical with the curtain 25, except that it is longer, whereby its lower outer edge will reach the ground A at a considerable distance from the curtain 25, as in Fig. 2. The curtain cover 26 is provided with triangular end members 28 and 29, whose angular upper edges are permanently secured to the end edges of the member 26, and in the junctures of the edges of the members 28 and 29 with the member 26 the respective ropes 30 and 31 are secured, which ropes extend beyond the member 26 at both the top and the bottom. The upper ends of each of the ropes 30 and 31 are provided with a ring 32 to fit over a pintle 7; and their lower ends are adapted to be secured to their respective stakes 33 and 34, as shown in Fig. 1.

By the above it will be seen that I provide an auxiliary room off one side of the main portion of the tent.

Numeral 35 denotes a fabric floor for said auxiliary room, and it lies loosely on the grass, extending between the ends 28 and 29, and its inner edge extends under the run-board C, and its outer edge is provided with swivel-headed fasteners 36, which when turned horizontal will enter the respective eyes 37, then when the heads are turned vertically the members 26 and 35 will be secured together, as in Fig. 2.

By the removal of curtain 25 the auxil-

iary room will be opened into the main room of the tent, after which the soil as it is removed to form the grave B may be deposited on the floor 35 of the auxiliary room, as shown, and during this time the workmen and the soil being removed, as well as the grave, will be protected from rain or other weather conditions.

After all of the earth H has been removed to form the grave B then the curtain 25 is placed in position to cut off the auxiliary room from the main room, whereby the removed soil will not be seen. The soil thus placed on the floor 35 will be entirely out of sight during the interment, and it will also be prevented from getting wet and muddy in the event of rain, and the grass thereunder will be protected, as the soil will be excavated for only a short time. After the interment the curtain 25 can be removed and the soil can be shoveled back into the grave, during which the workmen will be protected from the weather. This arrangement will also prevent any water washing the soil into the grave after it has been removed. And furthermore no suggestion of a pile of soil will be visible during the interment.

It is of course to be understood that all of said sides, the top, and the floor 35, are of fabric construction, the various parts being separable with relation to each other, and the entire construction can be rolled up into a small compass of space for transportation or storage, to be used when required.

I desire that it be understood that various changes may be made in the several details of construction and operation without departing from the spirit of the invention and without sacrificing any of the advantages thereof which are new and useful.

Having now fully shown and described my invention, what I claim and desire to secure by Letters Patent of the United States, is—

1. In combination with the main portion of a tent, an auxiliary apartment formed by a curtain cover extending from the eve of one side of the main tent at an angle to near the surface of the ground, ends connected to said curtain cover, a fabric floor for the auxiliary apartment, means for connecting the outer edge of said floor to the lower edge of said cover, the auxiliary compartment being adapted to be opened into the interior of the main tent or to be separated therefrom by the removal or the placing in position of a section of the wall of the main tent.

2. In combination with a main tent having a curtain portion adapted to be opened and closed, a fabric extension for the main tent comprising a top member extending at an angle outward and downward from above said curtain portion to near the

ground, ends secured to the ends of said top member and extending to near the ground and to the main tent on each side of said curtain extension, a floor for said extension, 5 the same extending inside the main tent through the opening which is adapted to be closed by said curtain member, means for

detachably securing the lower edge of the top and the lower edges of the ends to said floor, means for detachably securing the inner edges of said ends to the main tent, and means for detachably securing the lower edge of the top to the ground. 10

JAMES M. DODDRIDGE.
